REFRIGERATING APPARATUS

Richard S. Gaugler, Dayton, Ohio, assignor to
 General Motors Corporation, Dayton, Ohio, a
 corporation of Delaware

Application March 29, 1935, Serial No. 13,720

6 Claims. (Cl. 62—108.5)

This invention relates to refrigeration and particularly to freezing trays used in the freezing compartment of a cooling element of a domestic refrigerator. Flexible non-metallic trays have heretofore been used in domestic refrigerators for freezing water into a plurality of ice blocks or cubes. These trays while being constructed to facilitate the removal of ice cubes therefrom, after the tray has been removed from its support on the cooling element of a refrigerating system, have not been entirely satisfactory. For example, the flexible rubber trays now in use quite frequently become bonded to cooling elements to such a degree that they cannot be removed from the element without damaging or tearing the rubber walls thereof. In other words, during certain conditions within a household refrigerator or after prolonged operation of the refrigerating system associated therewith, a sufficient amount of moisture is condensed on the refrigerating surface of the cooling element, in the form of frost or ice, to cause the tray to become frozen in the cooling element. This frost frequently attains such a thickness as to build up around sides of the tray to such a height that the flexible tray cannot be moved by force applied to the handle of the tray by hands of the housewife or user. Therefore to remove the tray from the cooling element without applying enormous force thereto or without damaging same it would be necessary to defrost or melt the ice and frost from the cooling element irrespective of whether such defrosting was desired at that particular time. My invention is directed to an improvement for facilitating removal of a flexible tray from its support on a cooling element or evaporator of a refrigerating system under the conditions explained to avoid the necessity of defrosting the element.

An object of the present invention is to provide an improved tray from which the frozen contents may be easily removed and which tray may be conveniently handled either when filled with water or frozen substance.

Another object of the invention is to provide an improved flexible non-metallic tray having a reinforcing metal frame or support which will not interfere with flexing of the tray to facilitate removal of its frozen contents.

A further object of the invention is to provide a flexible non-metallic tray with a metal frame or support which, when force is applied thereto, twists one portion of the frame relative to another portion thereof to break a bond between the tray and its support on the cooling element.

A still further object of the present invention is to provide a flexible non-metallic tray with a metal wire frame or support which is positioned under the tray and has loose ends extending outwardly of the front thereof and tied together with a movable member adapted to be rotated to cause one of the legs of the frame beneath the tray to be elevated relative to the other leg to thereby loosen or free the tray from its support on a cooling element.

Further objects and advantages of the present invention will be apparent from the following description, reference being had to the accompanying drawings, wherein a preferred form of the present invention is clearly shown.

In the drawings:

Fig. 1 is a front view of a cooling element of a refrigerating apparatus of the household type showing trays embodying my invention supported by the element;

Fig. 2 is an enlarged vertical sectional view taken on the lines 2—2 of Fig. 1 through the cooling element and showing the trays in section and their supporting frame in elevation;

Fig. 3 is a vertical sectional view taken on the lines 3—3 of Fig. 2 showing the tray frame in normal position;

Fig. 4 is a view similar to Fig. 3 and shows one leg of the tray frame elevated relative to the tray support on the cooling element;

Fig. 5 is a view similar to Fig. 4 and shows the opposite leg of the tray frame elevated relative to the tray support on the cooling element;

Fig. 6 is a perspective view of the tray and its frame;

Fig. 7 is a rear plan view of the tray; and

Fig. 8 is an enlarged sectional view taken on the line 8—8 of Fig. 1 showing a knob fastened to the ends of the tray frame.

Referring to the drawings the reference character 10 designates an evaporator or cooling element adapted to be mounted in the food storage compartment of a household refrigerator cabinet and adapted to be connected to any suitable or conventional refrigerant liquefying and circulating unit (not shown). The evaporator 10 is preferably of the sheet metal variety of the type disclosed in the patent to Ernest Dickey, No. 1,972,551 of Sept. 4, 1934 and includes a plurality of refrigerated walls 11 forming a sharp freezing compartment 12. A refrigerated shelf 13 divides compartment 12 of evaporator 10 into a plurality of compartments and forms a flat support for receiving receptacles or trays adapted to contain a substance to be congealed or frozen. The dot- 55

dash lines indicated by the reference character 15 in Fig. 1 represents a coating or layer of frost or ice which, as hereinbefore explained, forms on walls of the evaporator 10 during certain conditions within a food storage compartment of a refrigerator cabinet or after prolonged operating of the refrigerating system connected to the evaporator. The reference character 16 designates as a whole a flexible receptacle or tray which is preferably moulded in one piece from soft flexible high grade rubber. The tray 16 has partitions 17 therein dividing the interior thereof into a plurality of longitudinal rows of separate ice-forming compartments or pockets 18. These partitions may be split a considerable distance downwardly from their top edge or they may have small openings interconnecting the pockets 18 to permit equalization of the water level in all the pockets when the tray is filled with water as is conventional and well-known to those skilled in the art.

Tray 16 has a boss 19 formed or moulded on and extending outwardly of the outer surface of the rear wall of the tray. A pair of bosses 21 and 22 similar to boss 19 are formed on and extend outwardly of the outer surface of the front wall of tray 16. Boss 19 at the rear of tray 16 has a horizontally disposed opening therethrough. Bosses 21 and 22 each have an opening therethrough which extend upwardly at the angle. The bosses 19, 21 and 22 may be of any desired shape or form and are for a purpose to be hereinafter more fully described.

The tray 16 is adapted to be supported on and carried by a metal frame, the top plan view of which is substantially U-shaped in contour. The metal frame for tray 16 comprises a round wire member generally designated by the reference character 24 including portions extending under the tray and other portions extending upwardly along the back and front walls of the tray. The portions of wire member 24 extending under the tray 16 includes two straight portions 25 and 26 which fit in grooves 27 provided in the bottom wall of the tray and extend longitudinally therewith. The straight portions 25 and 26 of wire member 24 are rigidly connected together by an integral inverted U-shaped portion 28 at the rear of tray 16 the yoke of which U-shaped portion extends through the opening provided in boss 19. The longitudinally extending straight supporting portion 25 of wire member 24 has an upwardly directed portion 29 at the front of the tray 16 which passes through the opening provided or formed in boss 21. The other straight portion 26 of member 24 has an upwardly bent portion 31 at the front of the tray 16 which passes through the opening formed in the boss 22. The ends 32 and 33 of the upwardly directed portion 29 and 31 respectively of wire member 24 are bent outwardly so as to extend in a horizontal direction from the front wall of the tray 16.

The wire frame member 24 is attached to the moulded flexible rubber tray 16 by forcing one of the free ends 32 or 33 thereof through the opening in the boss 19 at the back of the tray. The other portions, for example, one of the portions 29 or 31 of wire member 24 and one of the portions 25 or 26 are then pushed through the opening in boss 19 until the yoke of the U-shaped portion 28 has been brought into registration with the opening in boss 19. It is then necessary to force the end 32 and a part of the portion 29, of the wire member 24, through the opening in boss 21. Similarly the end 33 and a part of the

portion 31, of the wire member 24, is forced through the opening in boss 22. The tray 16 is of sufficient flexibility to permit shifting and twisting thereof without damaging same in carrying out the assembly operations described of attaching the wire frame 24 to tray 16.

After the wire frame member 24 has been attached to tray 16 the free ends 32 and 33 of member 24 are tied together. An elongated metal member 35 (see Figs. 6 and 8) has a plurality of openings 36, 37 and 38 provided therein and these openings are utilized for tying the free ends 32 and 33 of wire member 24 together and for attachment to member 35 of a knob or the like element. The hole or opening 36 in metal member 35 receives the end 32 of wire member 24 and this end 32 is secured to the member 35 by a screw 39. The hole or opening 38 in metal member 35 receives the end 33 of wire member 24 and this end 33 is secured to the member 35 by a screw 41. The ends 32 and 33 of wire member 24 being thus secured to member 35 are movably tied together relative to one another. A knob or the like element 43 having its circumferential surface knurled, as at 44, is provided with a cavity 45 of a contour similar to the outline of the tying member 35 is placed over the member 35 and secured thereto by a screw 46.

In the ordinary use of the device of the present invention the tray 16 is filled with water, or any other substance to be congealed or frozen, and is then inserted in the cooling element 10 and positioned upon the freezing shelf 13 or upon the bottom wall of the evaporator. It will be noted that when the device is positioned on the support of the cooling element the bottom walls of the pockets or compartments 18 of tray 16 rest on the flat supporting surface due to the rod portions 25 and 26 of member 24 being received in the grooves 27 of the tray and being flush with the bottom thereof. After the contents of the tray has been frozen the tray ordinarily becomes frozen or bonded to its support and if it is desired to remove the tray 16 from the cooling element the knob 43 of the device may be manually rotated in one direction, as shown in Fig. 4 of the drawings, to break the ice bond between the tray and its support longitudinally along one side of the bottom of the tray. This rotating movement of knob 43 causes a twisting force to be applied between the longitudinal straight portion 25 and 26 of member 24 and thus elevates the front part of portion 26 of member 24. The elevation of portion 26 of member 24 causes the bottom wall on one side of tray 16 to be substantially peeled from its support. To remove the other side of the bottom wall of tray 16 from the support the knob 43 is rotated in an opposite direction, as shown in Fig. 5 of the drawings, and this rotation of knob 43 causes a twisting force to be applied between the straight portions 25 and 26 of member 24 and thus elevates the front part of portion 25 of member 24. The elevation of portion 25 of member 24 causes the bottom wall on the opposite side of tray 16 to be substantially peeled from its support. Both sides of the bottom of tray 16 being loosened from its support in the manner described thus frees the tray and permits same to be readily removed from the cooling element or evaporator 10.

It is to be noted that the spaced apart straight portions 25 and 26 of member 24 of the device prevents these portions from interfering with flexing of tray 16 to remove its frozen contents after the device is removed from the cooling ele-

ment. It is also to be noted that the construction and arrangement of the elements of the improved device are such as to cause loosening of certain of the frozen blocks or cubes from walls of their compartments during movement of member 34 to loosen the tray 16 from its support. Loosening of the frozen blocks during the act of breaking the ice bond between the tray and its support greatly facilitates removal of the blocks from their compartments after the tray has been removed from the cooling element. The device of the present invention has all the desirable characteristics of a conventional flexible rubber tray while at the same time being provided with means for readily and easily breaking an ice bond between the tray and its support.

From the foregoing it will be seen that I have provided an improved device which facilitates carrying and handling of a flexible non-metallic ice tray. My improved device provides a means for moving the tray relative to its support on a cooling element and thereby insures removal of the tray from the cooling element irrespective of the amount of frost or ice accumulated on the element. My improved device provides a means which substantially peels a flexible non-metallic tray from its support on a cooling element to thereby prevent tearing of the material from which the tray is moulded.

30 While the form of embodiment of the invention as herein disclosed, constitutes a preferred form, it is to be understood that other forms might be adopted, all coming within the scope of the claims which follow.

35 What is claimed is as follows:

1. In combination with a cooling element of a refrigerating system having a support thereon for receiving and supporting an ice tray, a flexible non-metallic freezing tray on the support of the cooling element, a metal supporting device for carrying and positioning said tray on the cooling element support, said metal supporting device comprising spaced apart portions underlying the tray bottom and extending longitudinally therewith, said spaced apart portions of said device having parts thereof secured to said tray to form a unitary construction, the ends of said spaced apart portions of said device being integrally joined together at one end of the tray, and the ends of said spaced apart portions of said device at the opposite end of said tray being movable relative to one another to cause one of the spaced apart portions of said device to move upwardly of the other thereof for breaking an ice bond between the tray and its support on the cooling element.

2. In combination with a cooling element of a refrigerating system having a support thereon for receiving and supporting an ice tray, a flexible non-metallic freezing tray on the support of the cooling element, a metal supporting device for carrying and positioning said tray on the cooling element support, said metal supporting device comprising spaced apart portions underlying the tray bottom and extending longitudinally therewith, the ends of said spaced apart portions of said device being integrally joined together at the rear of the tray, and the ends of said spaced apart portions of said device at the front of said tray being movable relative to one another to cause one of the spaced apart portions of said device to

move upwardly of the other thereof for breaking an ice bond between the tray and its support on the cooling element.

3. In combination with a cooling element of a refrigerating system having a support thereon for receiving and supporting an ice tray, a flexible non-metallic freezing tray on the support of the cooling element, a substantially U-shaped metal wire supporting device for carrying and positioning said tray on the cooling element support, the legs of the U-shaped supporting device extending longitudinally with and underlying the tray, the ends of the legs of said U-shaped supporting device being movable relative to one another to cause one of the legs to move upwardly of the other leg for breaking an ice bond between the tray and its support on the cooling element.

4. In combination with a cooling element of a refrigerating system having a support thereon for receiving and supporting an ice tray, a flexible non-metallic freezing tray on the support of the cooling element, a substantially U-shaped metal wire supporting device for carrying and positioning said tray on the cooling element support, the integral connecting yoke of the legs of the U-shaped supporting device being secured to the back wall of said tray, the legs of the U-shaped supporting device extending longitudinally under the tray, and the ends of the legs of the device being secured to the front wall of said tray and being movable relative to one another to cause one of the legs to move upwardly of the other leg for breaking an ice bond between the tray and its support on the cooling element.

5. In combination with a cooling element of a refrigerating system having a support thereon for receiving and supporting an ice tray, a flexible non-metallic freezing tray on the support of the cooling element, a substantially U-shaped metal wire supporting device for carrying and positioning said tray on the cooling element support, the legs of the U-shaped supporting device extending longitudinally with and underlying the bottom of the tray, the ends of the U-shaped supporting device being tied together by a rigid member, and a knob or handle for moving the rigid member to cause movement of the ends of the legs of the device relative to one another for moving one of the legs upwardly of the other leg to break an ice bond between the tray and its support on the cooling element.

6. In combination with a cooling element of a refrigerating system having a support thereon for receiving and supporting an ice tray, a flexible non-metallic freezing tray on the support of the cooling element, a substantially U-shaped metal wire supporting device for carrying and positioning said tray on the cooling element support, the integral connecting yoke of the legs of the U-shaped supporting device being secured to the back wall of said tray, the legs of the U-shaped supporting device extending longitudinally under the tray, the ends of the legs of the device being secured to the front wall of said tray and having a rigid member tying the same together, and a knob or handle for moving the rigid member to cause movement of one of the legs of the supporting device upwardly of the other leg thereof to break an ice bond between the tray and its support on the cooling element.

RICHARD S. GAUGLER.
